TWISTER HEAD DRIVING MECHANISM FOR
WOOL SPINNING MACHINESFrancis B. Kelliher, Whitinsville, Mass., assignor
to Whiting Machine Works, Whitinsville, Mass.,
a corporation of Massachusetts

Application October 4, 1951, Serial No. 249,655

2 Claims. (Cl. 57—93)

1

This invention relates to machines particularly designed for spinning wool or other relatively long textile fibers.

In one commercial type of wool spinning machine, a twister head is associated with each spinning spindle and these twister heads are located between the feed roll and the delivery roll of the spinning frame. The delivery roll is rotated at higher surface speed than the feed roll, so that a desired draft takes place in the roving between these two rolls.

The twister heads are to give the rovings a false twist as the rovings are being drafted. This false twist is thereafter removed as the rovings leave the delivery roll.

The amount of false twist for most favorable results is dependent on the stock or material, on the amount of draft and on the yarn count, and varies widely under different conditions.

It has been customary to vary the twister head speed by changing gears or sprockets in the twister head drive, and upwards of twenty-five change gears or change sprockets were commonly supplied with a wool spinning machine. This "cut-and-try" method of determining the most favorable twister head speed was time-consuming and expensive, and the results were often only approximate.

It is the general object of my present invention to provide means in a wool spinning machine by which the relative speed of the twister heads may be progressively varied and adjusted while the machine continues in operation. The changing results are plainly visible to the operator, who can thus quickly select the most favorable twister head speed for the particular conditions of operation.

My invention further relates to arrangements and combinations of parts which will be hereinafter described and more particularly pointed out in the appended claims.

A preferred form of the invention is shown in the drawings, in which:

Fig. 1 is a sectional end elevation, showing parts of the driving mechanism of a wool spinning machine; and

Fig. 2 is a front elevation of certain driving connections.

Referring to the drawings, I have shown a drum 10 over which the rovings R pass from a supply roll or spool S to a pair of feed rolls 11 and 12, the roll 12 being positively rotated. Each roving then passes through a twister head T to a pair of delivery rolls 14 and 15, and the relative

surface speeds of the driven rolls 12 and 14 is adjusted to produce the desired draft.

The drafted rovings R then pass through thread guides 17 to travelers 18 on spinning rings 20 supported in fixed ring rails 21. The rovings then pass to bobbins B on spinning spindles 22 mounted on vertically movable spindle rails 24.

The twister heads T are rotated by a twister cylinder 30 through bands 31, and the spindles 22 are rotated from a main or spindle-driving cylinder 35 through bands 36.

The specific means for driving and vertically reciprocating the spindles 22 and bobbins B forms no part of the present invention and may be of the construction disclosed in the prior Kooistra Patent No. 1,820,310, issued August 25, 1931.

Preferred driving mechanism for the main or spindle-driving cylinder 35 is shown in Fig. 2 and comprises a motor M which is connected by belts 40 to a countershaft 42, which in turn is connected by a chain 44 and associated sprockets to the main shaft 50 which rotates the main cylinder 35. The speed of the main cylinder 35 may be varied by changing the speed of the motor M, or by providing suitable variable-speed pulleys for the belts 40.

A countershaft 60 is driven from the main shaft 50 through a chain 62 and associated sprockets, and the countershaft 60 is connected with the twister cylinder shaft 64 through a driving belt 66 and associated variable-speed pulleys 70 and 72.

These variable speed connections may be of any usual or suitable commercial form, and in themselves form no part of my present invention, which is not to be limited to the particular variable-speed construction shown.

In Fig. 2 I have shown a conventionalized form of the well-known Reeves type of variable speed driving mechanism.

As shown, a hand wheel 75 is connected through a worm 76 to a worm wheel 77 mounted on a sleeve 78. By angularly adjusting the sleeve 78, the axial spacing of the separate parts of the pulley 70 may be varied. The corresponding separate parts of the pulley 72 are yieldingly mounted, so that they may axially adjust themselves to the setting of the pulleys 70.

Details of similar adjusting structure are shown in Fig. 4 of Rosenfeld Patent #2,229,673, issued January 28, 1941.

The hand wheel 75 is preferably located at the side of the spinning frame, so that the operator can turn the hand wheel to vary the relative speed of the twister head cylinder 30, and

at the same time will be in a position to observe the effect of such change in relative speed on the operation of the machine. The best relative speed may thus be quickly selected.

By the provision of this manually adjusted variable speed mechanism at this strategic point in the twister head cylinder drive, much of the operator's time is saved. The results are more accurate, and the expense of providing a large number of change gears or change sprockets is avoided.

Having thus described my invention and the advantages thereof, I do not wish to be limited to the details herein disclosed, otherwise than as set forth in the claims, but what I claim is:

1. In a wool spinning machine, a plurality of spinning spindles, means to drive said spindles, a plurality of twister heads, a twister cylinder and shaft, driving connections between said cylinder and said twister heads, a power shaft, a variable-speed mechanism between said power shaft and said cylinder shaft, and manual control means for said variable-speed mechanism ef-

fective to vary the twister head speed while the spindle speed remains unchanged.

2. In a wool spinning machine, a plurality of spinning spindles, means to drive said spindles, a plurality of twister heads, a twister cylinder and shaft, driving connections between said cylinder and said twister heads, a power shaft, a variable-speed mechanism between said power shaft and said cylinder shaft, and manual control means for said variable-speed mechanism effective to vary the twister head speed while the spindle speed remains unchanged, and said manual control means being located at the side of the machine for actuation by an operator in yarn-observing position.

FRANCIS B. KELLIHER.
